Primary Examiner—Sandra L. Morris

[57] **CLAIM**

The ornamental design for a toy winged figure, as shown and described.

DESCRIPTION

FIG. 1 is a front elevational view of a toy winged figure, showing my new design;

FIG. 2 is a side elevational view thereof, the other side being identical;

FIG. 3 is a back elevational view thereof; and,

FIG. 4 is a top plan view thereof.
